Renewed September 10, 1932

21 Claims. (Cl. 214—16)

This invention relates to improvements in the structure of buildings and more particularly to improvements in the structure of buildings utilized principally for warehouse and factory purposes.

The invention is concerned with the construction of buildings for the purposes set forth, wherein provision is made for the handling of trucks from the ground floor to various upper floors, such provision consisting of arrangements of truck landing pits at the various floors, whereby the trucks may be moved from elevators into the pits in position for loading or unloading.

An object of the present invention is to provide arrangements whereby trucks of various overall height including the height of the load thereof may be accommodated on floors, the head room of which is less than the overall height before mentioned.

Another object of the invention is to provide such arrangements on any or all of the floors above ground level as may be desired.

Another object of the invention is to provide truck landing pits at any of the desired floors, such pits being of dimensions to permit the loading or unloading simultaneously of more than one truck brought to the pit by a single elevator.

A further object of the invention is to provide, in connection with multiple elevators, truck landing pits on various floors of such dimensions as to permit a truck to be manoeuvered into position to be accommodated by an elevator other than the one which originally delivered it to the pit.

A further object of the invention is to provide in connection with the arrangement hereinbefore specified for accommodating trucks of excessive overall height, relative to floor head space, truck pits so constructed as to permit the unloading or loading of more than one truck simultaneously and to permit manoeuvering of the trucks from one elevator to another, as occasion may demand.

A still further object of the invention is to provide temporary or movable means whereby a truck may be loaded or unloaded while in a truck landing pit and out of normal loading or unloading area.

According to the present invention it is contemplated that trucks having various over-all heights may be accommodated on any or all floors of a building, wherein the head room between the floor of one story and the ceiling thereof is less than the over-all height of the truck and its load. Ordinarily where it is desired to re-

ceive trucks of more than ordinary height on the various floors of a building, it is necessary to construct the building with the floors spaced apart a distance sufficient to receive the trucks. Since only a certain amount of the space on a floor can be utilized for storage purposes, the remaining space existing above this accessible space becomes wasted with a resultant exorbitant increase in the building cost. The present invention overcomes this difficulty in the manner to be set forth hereinafter, thereby permitting buildings to be constructed with floors of less than normal head space with a resultant decrease in cost of construction. To accomplish this purpose the truck landing pit of one floor is made deeper than the truck landing pit of the floor immediately thereabove with the result that a head room is created which is greater than the normal head room of the floor. This arrangement of deep pit on one floor together with a shallow pit on the floor directly thereabove may be combined with pits of a normal depth immediately adjacent thereto or may be so staggered that each floor in the building is capable of accommodating trucks of excessive over-all height, the pits for such trucks being in staggered relation, one floor with respect to the other. It is to be understood of course that if desirable the arrangement for accommodating trucks of over-all height may be provided on such floors as necessary with the result that the remaining floors are provided with truck landing pits of normal depth and size.

The invention further contemplates the provision of truck landing pits on any or all floors of such dimensions as to accommodate more than one truck brought to the floor by the same elevator for simultaneous loading or unloading. To this end the normal truck landing pit, the floor of which is below the main floor, is extended away from the elevator shaft and caused to diverge outwardly so that at least a pair of trucks can be accommodated side by side in the enlarged area of the truck landing pit. In connection with such an arrangement and where a bank of elevators is used with connecting truck landing pits, the invention contemplates the connecting of the truck landing pits in such a manner that a truck delivered into one section of the pit by one elevator can be manoeuvered into position to be accommodated by a different elevator. This arrangement is of paramount importance since occasionally the mechanism of an elevator may fail temporarily, whereupon under former prac-

tice a truck would be stranded at one of the floors until the mechanism could be repaired.

In another phase of the invention the arrangement previously described of extending the truck landing pits may be incorporated with truck landing pits of various depths to accommodate trucks of differing over-all heights, whereby more than one truck of such excessive height may be loaded or unloaded simultaneously after being delivered to a floor by one elevator. Furthermore, if the bank of elevators be employed, the invention provides an arrangement whereby a truck in one pit of one head room may be manoeuvered into an adjacent pit of a different head room in the event of elevator mechanism tie up.

In a still further phase of the invention use is made in connection with truck landing pits of extended area of temporary and movable loading and unloading platforms which may be placed adjacent to a truck which is positioned in space ordinarily wasted. For example, if the enlarged part of the pit be filled to capacity with trucks, another truck may be positioned in the part of the pit immediately adjacent the elevators and the temporary platform moved into place to permit this latter truck to be loaded or unloaded. This arrangement is of especial importance in connection with warehouses, wherein the trucks are stored during the night and loaded or unloaded while so stored. The arrangement in this manner makes use of all available truck loading or unloading space, minimizing the loss of space due to truck maneuvering.

Still further objects, features and advantages of the present invention will become apparent by reference to the following detail description read in the light of the accompanying drawings, wherein

Fig. 1 is a plan view of one floor of a building in which provision is made for the accommodation of trucks of excessive over-all height relative to the floor head space, the figure showing the ramp connecting a pit of one depth with a pit of a different depth;

Fig. 2 is a section taken substantially on the lines 2—2 of Fig. 1 with the addition that the section also passes through more than one floor to illustrate the manner in which pits having head space greater than the normal head space of a floor may be provided in staggered relation on successive floors.

Fig. 3 is a section taken substantially on the lines 3—3 of Fig. 4 and is a plan view of the floor having the normal truck landing pit extended and diverged away from the elevator shaft so that more than one truck delivered by a single elevator can be accommodated for loading or unloading simultaneously and also showing the provision of a temporary platform to be positioned in the rear of a truck occupying the landing pit space closest the elevator shaft, the arrangement being such that the pits may be of uniform depth or may be of varying depths as desired.

Fig. 4 is a section taken substantially on the line 4—4 of Fig. 3.

Figs. 5, 6 and 7 are sections taken on substantially the lines 5—5, 6—6 and 7—7 respectively of Fig. 3, in which the adjacent truck pits are illustrated as being of varying depth to permit the accommodation of trucks of varying over-all heights.

Figs. 8, 9 and 10 are sections similar to Figs. 5, 6 and 7 respectively, with the difference that the adjacent pits are of uniform depth.

Fig. 11 is a plan view taken substantially on

lines 11—11 of Fig. 12 showing an arrangement wherein the landing spaces constructed in accordance with the present invention are provided on each side of elevator shafts.

Fig. 12 is a section taken substantially on lines 12—12 of Fig. 11.

Fig. 13 is an enlarged section taken substantially on lines 13—13 of Fig. 11.

Fig. 14 is a plan view taken substantially on lines 14—14 of Fig. 15, and showing an arrangement of landing spaces situated between spaced elevator shafts with removable platforms in position in said spaces.

Fig. 15 is a vertical section taken substantially on lines 15—15 of Fig. 14 and showing a multiplicity of floors having landing spaces in staggered relation.

Referring now to the drawings and more particularly to Figs. 1 and 2, 10 and 11 represent the shafts for elevators capable of transporting trucks from one floor to another. The elevators mounted for movement within the shafts 10 and 11 may be of any desired type, such as that shown in the patent to Russell G. Cory, No. 1,730,645, issued October 8, 1929, or the type shown in our co-pending application Serial No. 399,196, filed October 12, 1929. Reference characters 12 represent the building columns adjacent the elevator shafts between which columns extend floors 13 and 14 of truck landing pits, such floors being below the normal floor level 15. The floor level 15 of any one of the floors may be called the main floor level in relation to the depressed pits. As shown in Fig. 1, the floors 13 and 14 extend away from the shafts 10 and 11 to approximately the columns 16 used in the structure of the building.

Inasmuch as the over-all height of some trucks plus their load is greater than the normal head space between the floors of a building, it becomes necessary to provide some construction whereby these trucks of excessive over-all height may be accommodated. For this purpose the arrangement illustrated in Figs. 1 and 2 and illustrated very clearly in Fig. 2 is provided. As shown, the floor 13 of one pit extends a small distance below the floor 14 of another pit. On the next floor the floor 13 is positioned immediately above floor 14, while floor 14 of the second story is positioned above floor 13 of the former story. From this it will be seen that with a distance A from floor level to floor level existing, such distance is not sufficient to accommodate a truck and load as shown in dotted lines in Fig. 2. For this reason the respective deep and shallow pits 13 and 14 are placed in staggered relation, one above the other, so that a distance C greater than the distance A is provided in one case, and a distance B smaller than distance A in another case. This distance B may be sufficient to accommodate trucks of a conventional height.

It will be noted that walls 17 are provided extending from the floor level 15 to the level of the respective pits 13 and 14, these walls 17 being shown at the right hand side of the drawings as permanent walls, while at the left hand side of the drawings the same walls are shown in dotted lines to indicate that should more than two elevators shafts be provided, the respective pits 13 and 14 on the various floors can be extended to the left to accommodate trucks delivered by the additional elevators. In the present instance the arrangement shown is adapted for use with elevators travelling in two pits, but it is to be understood that no limitation is to be

placed on the invention as to the number of elevator shafts and corresponding pits employed. Since mechanical trouble sometimes causes the tie-up of elevators, it is advantageous that some provision be made to permit a truck in one pit to be maneuvered into another pit, so that it can be transported by an elevator different from the one which originally delivered it to the floor. In other words, it is desirable that the pits be so arranged that they are in truck-transit communication with one another. In this particular type of structure utilizing adjacent pits of different floors levels, ramps 20 are provided connecting the respective pit levels 13 and 14 so that the truck can be maneuvered from either pit to the other. It will be apparent of course that should a truck in one of the deep pits 13 be loaded to the maximum height, it will be necessary to remove part of the load before the same could be maneuvered to a pit level 14. Inasmuch as mechanical breakdowns are of infrequent occurrence, this expediency will not be resorted to frequently. It is equally apparent that trucks being loaded or unloaded while on the pit floors 14 can be maneuvered readily to pit floors 13. This possible truck movement is shown by arrows in Fig. 1.

Referring now to Fig. 3 and the figures formed as sections thereof, it will be seen that an arrangement is provided wherein a number of trucks can be accommodated in pits for simultaneous unloading or loading, such trucks being transported to the respective pits by the same elevators. For this purpose shafts 10 and 11 are shown, as before, extending the height of the building and having openings into the respective floor levels, such openings being into the truck pits rather than the floor level proper. As before, the walls, etc., shown at the right hand side of Fig. 3 are indicated as being permanent walls, while the walls at the left hand of the figure are shown in dotted lines to indicate that more than the two shafts 10 and 11 may be employed.

Assuming that we have a pit floor 25 opposite shaft 11, it will be seen that this floor 25 extends straight backward from the elevator shaft a considerable distance to the normal floor level 30. As soon as one side of columns 31 of the building structure have been passed, however, the pit extends outwardly and backwardly at an angle as indicated by wall 32 to the columns 33, from which point the pit extends further in a direction parallel to the normal lay of the pit. By reason of this construction it is possible to position two trucks 35 side by side within the pit with the truck platforms in contact with the unloading platform 30 as shown. The same type of arrangement is employed in connection with the shaft 10 with the result that at least two trucks can be delivered by the elevator in shaft 10 and backed against the unloading platform as before. Moreover it will be observed that with two trucks in the pit, either may be driven therefrom to the truck elevator. In other words, the trucks are optionally or selectively removable.

As conditions may require, the pit level 24 extending from shaft 10 and the pit level 25 extending from shaft 11 may be of the same depth relative to the level 30 of the main floor, in which event it will be readily apparent that trucks loaded or unloaded while positioned in either one of the pits may be maneuvered into position to be transported by the elevator in either shaft. The detailed construction of the pits is shown further in the sections illustrated in

Figs. 8, 9 and 10, wherein the pits 24 and 25 are in effect continuous levels.

On the other hand, it is possible that conditions might require that the level of pit 24 be different from that of pit 25, for which purpose a ramp 40 would be employed, extending from one level to the other in the space between the edge of the elevator shafts and one of the columns 33. By means of this ramp it would be possible to maneuver a truck from one pit level to another. In this construction the line of separation of the levels in the enlarged pit space is indicated at 41.

Further variation in floor height can be secured by dropping the forward end of pit 25 below the normal level of that pit, the two levels of the pit being connected by a ramp 40^a.

As illustrated in Fig. 4, a pit 24 of a single shallow depth is located above the deep pit 25 in order to obtain increased head room as explained in connection with the pits 13 and 14 of Figs. 1 and 2.

In some types of business it is customary to store trucks for the night at various floors and to load or unload the trucks during the night. For this purpose where the extended truck pits as shown are employed, use is made of a temporary loading or unloading platform which may be positioned to permit an additional truck to be loaded or unloaded during the night or at any other time, such additional truck occupying space 105 ordinarily held open for the maneuvering of trucks. As shown clearly in Fig. 3, the trucks 35 may be positioned side by side against the unloading platform 30, while an additional truck 45 may be positioned in the pit 25 in the space 110 between the edge of the shaft 11 and the remote edges of columns 33. This space is ordinarily reserved for the movement of trucks from the loading platform 30 to the elevator, or from one pit to another. With the truck in this 115 position, use may be made advantageously of a temporary platform such as that which is formed by means of a collapsible bridge 50 formed of two similar sections, one end of one of which is hinged at the floor level 30 and the similar 120 end of the other of which is hinged adjacent the column 33. The horizontal expanse of each section may be split and pivotally joined, so that the platform can be raised out of the line of truck movements. Supporting members 51 support the ends of the sections 50 remote from their main pivotal point. Removable hoist lines 52 may be employed to raise the platforms out of the line of truck movements. It will be understood of course that these hoist lines may be disengaged from the platforms when the same are in actual use or not as may be desired.

These temporary and movable platforms while shown in the nature of bridges pivotally mounted are not necessarily of this type of structure but 125 may be of any type of structure which can be efficiently employed in connection with truck landing pits and loading spaces at normal floor level. Furthermore, the temporary platforms may be employed with pits of uniform floor level 130 or pits of varying floor levels as shown in the drawings.

Figs. 11, 12 and 13 illustrate the manner in which landing spaces of the character previously described can be utilized on each side of elevator 145 shafts so that an elevator may discharge from either end thereof. As shown, the shafts 10 and 11 have adjacent thereto landing spaces 24 and 25 of varying depths, such spaces being extended rearwardly from the shafts to permit the accom- 150

modation of an increased number of trucks. These spaces are provided on each side of the bank of elevator shafts so that increased facilities for loading or unloading trucks on a single floor are provided.

Fig. 12 shows a vertical section of a building illustrating the manner in which the truck pits can be arranged on each side of the bank of elevator shafts. As clearly indicated, the pits or 10 landing spaces 24 of one floor are over landing spaces 25 of the floor immediately therebelow so that a landing space is created between the floors of a height greater than the head space of the floors. This arrangement being designed merely 15 to illustrate the adaptation of the invention to a multiplicity of floors is not to be limited to such an arrangement since it is clearly evident that the landing spaces can be provided on such floors as desired and in whatever relation one 20 to another necessary for the purposes in view.

Figs. 14 and 15 illustrate the manner in which landing spaces may be provided between two elevator shafts spaced apart longitudinally. In these figures, 60 and 61 represent the shafts 25 accommodating elevators between which shafts are provided landing spaces 62 and 63, the landing space 62 being at a higher level relative to the level of the main floor than landing space 63. The two landing spaces are joined at approximately 30 the mid point between the shafts 60 and 61 by a ramp 64. In order that goods may be loaded or unloaded from trucks positioned in these respective spaces, use is made of removable platforms 65, which may be of any desired 35 construction, for example, similar to the removable platforms 50 illustrated in previous figures. Since the exact construction of the platform is not an essential part of the invention, it is shown in the manner illustrated merely for explanation. 40 Since it may be desirable to provide truck landing spaces having a head space greater than the normal head space of the floor, the landing pits 62 and 63 on successive floors may be staggered as shown in Fig. 15 to accomplish this 45 result. By providing the ramps 64 connecting the various pits, it is possible in the event of mechanical trouble in one elevator shaft to maneuver a truck from one pit to the other in alignment therewith into position to be handled by 50 the other elevator.

From the foregoing it will be seen that the structure according to the present invention provides improvements in buildings, wherein trucks are moved from one floor to another, such improvements permitting the ready movement of the trucks; efficient loading and unloading of a multiplicity of trucks and the accommodation of trucks of normal over-all height and excessive over-all height. By reason of the use of pits or 55 shallow and deep floor level, relative to the main floor level, it is possible to secure a head space in one instance greater than the head space between normal floors, provided these pits of varying depth are staggered one floor above the 60 other, relative to each other. Furthermore, a building may be so constructed that each floor is provided with these pits of varying depth, or any particular floor in the building may be so constructed as the requirements of the particu- 65 lar use to which this building is put may demand. By reason of the elongation of the truck landing pits beyond that distance required for the 70 accommodation of a single truck and the widening of the pit in this elongated part, it is possible to accommodate normally twice the num- 75

ber of trucks transported by a single elevator as otherwise could be accommodated. In addition to this increased loading and unloading facilities, at certain times a still further truck may be accommodated for loading or unloading by the use of the temporary platform as before described. Should the pits be extended to a degree warranting it, additional temporary platforms may be utilized as required.

It will be apparent that the elongation of the truck landing pits may be equally well adapted to adjacent pits of uniform depth or adjacent pits of varying depth, in which latter event the ramp connecting the pits permits movement of trucks from one pit to another, so that in the case of a mechanical breakdown in one elevator shaft, the trucks may be moved by an elevator in another shaft.

In instances where local fire laws place restriction on truck landing spaces on other than ground floors, fire walls of a movable character may very readily be supplied to enclose the various landing spaces for protective purposes. Since the construction of such fire walls forms no part of the present invention, the same is not illustrated in detail herein.

By "trucks", as used throughout the specification and claims, is meant vehicles of the type customarily employed in ordinary inter-municipal or intra-municipal haulage work and having their own motive power, such as an internal combustion engine. By "truck elevators" is meant elevators designed or intended for elevating trucks of the type defined.

Furthermore it will be readily apparent that while the invention has been illustrated in connection with a pair of shafts for elevators, that no limitation as to the number of shafts in the bank need be imposed, since the invention adapts itself to any number of shafts.

For the reasons hereinbefore set forth, it is to be understood that the invention is not to be limited to the illustrated embodiments, but is to be limited only by the scope of the following claims.

We claim:

1. In a building of the character described having a plurality of floors, the combination with a truck elevator serving said floors of truck landing spaces at certain of said floors at levels below the respective main floor levels, one of said landing spaces being at a lower level relative to its main floor than the level of the landing space immediately thereabove relative to its main floor level.

2. In a building of the character described having a plurality of floors, the combination with a truck elevator serving the floors of truck landing spaces on certain floors, the level of one of said landing spaces being lower than the level of a landing space immediately thereabove relative to the levels of the respective floors whereby a head space is created between the landing spaces greater than the head space between the floors.

3. In a building of the character described having a plurality of floors, the combination with truck elevators serving said floors of truck landing spaces at certain of said floors at levels below the level of the respective main floors, the landings at one floor having varying levels relative to their main floor level, the landings at the floor immediately thereabove having varying levels relative to their main floor level and in staggered relation to the levels of the landings therebelow.

4. In a building of the character described hav-

- ing a plurality of floors, the combination with truck elevators serving said floors of truck landing spaces at certain of said floors at levels below the level of the respective main floors, the landings at one floor having varying levels relative to their main floor level, the landings at the floor immediately thereabove having varying levels relative to their main floor level and in staggered relation to the levels of the landings therebelow thereby creating head spaces between the landings of different heights. 5
5. In a building of the character described having a plurality of floors, the combination with truck elevators serving said floors of a truck landing space at one floor at a level below its main floor level, another landing space at the same floor at a different level below said main floor level, said landing spaces being joined by an inclined surface. 15
- 20 6. In a building of the character described having a plurality of floors, the combination with truck elevators serving said floors of a truck landing space at one floor at a level below its main floor level, another landing space at the same floor at a different level below said main floor level, said landing spaces being joined by an inclined surface, and similar landing spaces at the floor immediately thereabove, and in staggered relation to said first mentioned landing spaces.
- 30 7. In a building of the character described having a plurality of floors, the combination with truck elevators serving said floors of truck landing spaces at certain of said floors at levels below their main floor levels, said truck landing spaces being extended and widened to accommodate a plurality of trucks in substantially parallel position and an additional truck adjacent the elevator shaft. 35
- 40 8. In a building of the character described having a plurality of floors, the combination with a plurality of truck elevators serving said floors of a plurality of truck landing spaces at each of certain floors at levels below the respective main floor levels, said landing spaces being extended from the elevator shafts and widened to accommodate a plurality of trucks in substantially parallel position, the landing spaces on a floor being connected to permit truck movement from one space to another. 45
- 50 9. In a building of the character described having a plurality of floors, the combination with truck elevators serving said floors of truck landing spaces at certain of said floors at different levels lower than the levels of the respective main floors, the landing spaces of a floor being extended and widened and connected by an inclined surface adjacent the elevators, and similar landing spaces at the floor immediately thereabove in staggered relation to said first mentioned landing spaces. 55
- 60 10. In a building of the character described having a plurality of floors, the combination with elevators serving said floors of landing spaces at certain of said floors at levels below the levels of the respective floors, the landing space of the floor being extended from the elevator shaft and widened, and a temporary platform movable into said landing space in operative position relative to a truck therein and with its surface in substantial alignment with the floor surface. 65
- 70 11. In a building of the character described having a plurality of floors, the combination with a truck elevator serving said floors of landing spaces at certain floors at levels below that of the respective main floors, and temporary platforms movable into said landing spaces and with their surfaces in substantial alignment with the floor surfaces. 75
12. In a building of the character described having a plurality of floors, the combination with a plurality of elevators serving said floors of a plurality of landing spaces at each of certain of said floors adjacent the elevator shafts at levels below those of the respective floors, the landing spaces of a floor being connected for truck movement from one to another, and temporary platforms movable into said landing spaces and with their surfaces in substantial alignment with the floor surfaces. 80
13. In a building of the character described having a plurality of floors, the combination with a plurality of elevators serving said floors of landing spaces at a floor at different levels below the level of the floor, said spaces being extended and widened, similar landing spaces at the floor immediately thereabove in staggered relation to the landing spaces below the same, and temporary platforms movable into the respective landing spaces and with their surfaces in substantial alignment with the floor surfaces. 85
14. In a building of the character described having a plurality of floors, the combination with a plurality of elevators serving said floors of landing spaces at a floor at different levels below the level of the floor, said spaces being extended and widened, similar landing spaces at the floor immediately thereabove in staggered relation to the landing spaces below the same, the landing spaces of a floor being connected adjacent the elevator shafts to permit truck movement from one space to another, and temporary platforms movable into the respective landing spaces and with their surfaces in substantial alignment with the floor surfaces. 90
15. In a building of the character described having a plurality of floors, a plurality of truck elevators arranged side by side and serving said floors, at least one floor having a truck landing pit in front of each elevator and depressed below the normal floor level, the pits being sufficiently large and arranged in truck-transit communication whereby to permit a truck reaching one of said pits by one elevator to be maneuvered into another of said pits to leave the floor by another of said elevators. 105
16. In a building of the character described having a plurality of floors, a truck elevator serving said floors, a depressed truck landing pit on one of said floors, said pit having a first landing space at one depressed level and confronting the elevator, and a second landing space to the rear of the first landing space from the elevator, said second landing space being at a different level from the first landing space, and being connected with the first landing space by an inclined ramp. 110
17. In a building of the character described having a plurality of floors, at least two elevators arranged in side-by-side relation to each other and serving the floors, a first depressed truck-landing pit in front of one of the elevators, a second depressed truck-landing pit having a level lower than that of said first pit, the forward portion of said second pit being depressed below the normal level of the second pit and connected to the remainder of the second pit by an inclined ramp, and an inclined ramp connecting the depressed portion of the second pit with the first pit. 115
18. In a building of the character described having a plurality of floors, at least two elevators 150

arranged in side-by-side relation to each other and serving the floors, a first depressed truck-landing pit in front of one of the elevators, a second depressed truck-landing pit having a level 5 lower than that of said first pit, each of said truck-landing pits having a forward portion adjacent the elevator and of a width to accommodate a single truck, and each of said truck-landing pits having a rear portion widened to accommodate 10 a plurality of trucks, the forward portion of said second pit being depressed below the normal level of the second pit, an inclined ramp connecting the forward portion of the second pit with the first pit.

15 19. In a building of the character described having a plurality of floors, a plurality of truck elevators arranged in side-by-side relation to each other, at least one floor having at least two truck landing pits depressed below the normal level 20 of said floor, thereby forming an unloading platform at the level of the floor of a truck in one of said landing pits, said landing pits being arranged in front of two contiguous elevators, respectively one for each elevator, each pit being 25 widened so that the combined width of said pits is greater than the combined width of the elevators, said pits opening toward each other and being arranged so as to permit a truck reaching one of said pits by one of said elevators to be maneuvered into the other pit to leave the floor 30 by another of said elevators.

20. In a building of the character described

having a plurality of floors, a plurality of elevators arranged in side-by-side relation to each other, at least one floor having at least two truck landing pits depressed below the normal level of said floor, thereby forming an unloading platform at the level of the floor of a truck in one of said landing pits, said landing pits being arranged in front of two contiguous elevators, respectively, each pit being widened at its end farthest from the elevators so that the combined width of said pits at their widened end is greater than the combined width of the elevators, said pits opening toward each other and being arranged so as to permit a truck reaching one of said pits by one elevator to be maneuvered into the other pit to leave the floor by another elevator.

21. In a building of the character described having a plurality of floors, a plurality of truck elevators arranged side by side, at least one floor having at least two truck landing pits depressed below the normal level of said floor, one for each elevator respectively, thereby forming an unloading platform at the level of the floor of a truck in said landing pits, one of said pits being widened and being sufficiently large to permit the storage of a plurality of trucks with either selectively removable, and the combined width of the pits being greater than the combined width of the truck elevators.
